UNITED STATES PATENT OFFICE

151,171

PLASTIC FILM MATERIAL

Michael Angelo Susi, New York, N. Y., assignor
to Toscony Fabrics Inc., New York, N. Y., a cor-
poration of New York

Application July 16, 1949, Serial No. 3,961

Term of patent 3½ years

(Cl. D92—1)

To all whom it may concern:

Be it known that I, Michael A. Susi, a citizen of the United States, residing in the city of New York, county of New York, and State of New York, have invented a new, original, and ornamental Design for a Plastic Film Material, of which the following is a specification, reference being had to the accompanying drawing, forming a part thereof.

The figure on the drawing is a plan view of a plastic film material showing my new design.

A full width of the material is disclosed vertically on the drawing. A design unit is outlined by broken lines and is repeated over the fabric as indicated in regular succession.

I claim:

The ornamental design for a plastic film ma-
terial, shown and described.

MICHAEL ANGELO SUSI.
